UNITED STATES PATENT OFFICE.

MONTAGU BLATCHFORD, OF HALIFAX, ENGLAND, ASSIGNOR TO JOSEPH WILD & CO., OF NEW YORK, N. Y.

DESIGN FOR A CARPET-PATTERN.

Specification forming part of Design No. 5,768, dated April 16, 1872.

Specification describing a new and original Design for a Carpet, invented by MONTAGU BLATCHFORD, of Halifax, in the county of York, England.

The accompanying photograph fully represents my new design.

This invention relates to a new carpet design, composed entirely of a floral scroll, with bunches of flowers at the termination of the several convolutions, as shown.

I claim as my invention—
The design for a carpet, as shown and described.

MONTAGU BLATCHFORD.
